UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,157,159.

Specification of Letters Patent.

Patented Oct. 19, 1915.

Application filed December 16, 1909. Serial No. 533,387.

To all whom it may concern:

Be it known that I, HARRY J. HICK, a citizen of the United States, residing at Alliance, in the county of Stark and State 5 of Ohio, have invented certain new and useful Improvements in and Relating to Filing Appliances, of which the following is a specification.

This invention relates to a filing appliance. 10 The invention consists of a plurality of groups or sets of paper or slip-receiving holders which groups or sets are mounted upon an endless device, whereby each group is adapted to be brought successively into 15 position for ready and convenient manipulation and operation.

The invention further consists, in combination with a plurality of groups of holders, of index devices one for each group of holders and coöperating therewith, whereby an index or index device is moved into operable position at the time when its corresponding set of holders is in operable position.

For the purpose of illustration I have, in 25 the accompanying drawings, shown and herein described one form of filing appliance embodying my invention.

Figure 1 is a side elevation of a filing appliance embodying my invention, one side of the casing being removed. Fig. 2 is a front elevation of the filing appliance. Fig. 3 is a vertical section through the casing and sprocket wheels for the endless device. Fig. 4 is a side elevation of a set of holders in 30 operable position, somewhat enlarged to illustrate details of construction. Fig. 5 is an enlarged fragmentary plan view showing the index device.

In the drawings—1 indicates a casing or 40 housing, preferably comprising a back 1^a and side members 1^b, 1^c. The side members 1^b preferably extend forward as shown at 1^c to provide a suitable support for a desk top or table 1^d. The table 1^d is preferably trans- 45 parent so that the person operating the filing appliance may readily refer to an index, (to be hereinafter described), located underneath the said table. Below the table the casing may also be provided with a plurality of trays or drawers 1^e. While the 50 casing 1 illustrated in the drawings is shown as a portable casing, it will be understood

that the appliance may be built into a counter or other structure which will form part of or constitute the casing therefor.

2 indicates an endless device preferably comprising a pair of spaced endless chains 2^a, 2^a, each mounted upon sprocket wheels 2^b, 2^b, and 2^c, 2^c. The sprocket wheels 2^c are mounted near the top of the opposite side 60 members 1^b, 1^b, and are free to turn in their bearings. The sprocket wheels 2^b in the lower portion of the casing 1 are preferably fixed to a transverse shaft 2^d, carried by the side members 1^b, whereby the two chains will 65 always travel at the same rate of speed. If desired, the shaft 2^d may be extended through to the outside of the casing, as shown at 2^e, and have connected to it a crank or suitable motor for rotating it.

3 indicates a plurality of freely swingable frames, each carrying a set of slip holders 4. Each of the frames 3 preferably comprises a base 3^a, a back 3^b, and sides 3^c, the latter carrying pivot devices 3^d coöperating with 70 aligned special links in the chains 2^a for connecting and supporting the frame between the latter. The pivot devices 3^d are arranged at such point on the sides 3^c relative to the center of gravity of the frame when the 80 latter is carrying a set of holders 4, that the frame will hang downwardly and the holders will be supported in a substantially vertical position as the frame is moved from one point to another by the chains 2^a in their 85 up and down runs and movement around the sprockets 2^b, 2^c.

Each set of holders 4 comprises a series of pivotally mounted leaves 4^a carrying slip-holding devices 4^b. In the form of construction chosen for illustration in the drawings, the leaves 4^a are hinged together by devices 4^c at their lower ends, and the frontmost leaf is pivotally and removably fulcrumed upon the base 3^a of the 95 frame 3.

5 indicates a combined lock and guide device, one for each set of holders, pivotally supported at its rear end to the adjacent frame back 3^b, and provided on its front end 100 with a lip or latch 5^a to engage with the upper end of the front-most leaf of the adjacent set of leaves, and lock all the leaves of the set in upright position as shown in

Fig. 1; which is the normal position of the leaves, excepting when rotated downwardly upon the table.

With this construction it will be seen that when the respective sets of holder-leaves are moved by the endless device to a position adjacent to the table, by slightly pressing upward the device 5 the front leaf will be released from the lip 5^a, and it may then be swung downwardly either singly or jointly with one or more of the connected leaves, into horizontal position upon the table for rendering accessible the contents of the holders. This latter operation will move the remaining leaves upwardly, which in turn will through the engagement of the rearmost leaf with the device 5, throw the latter upwardly, whereby it will guide the rear leaf in its up and down movements. As the device 5 is preferably inclined when raised, it will automatically move forward and rearward the upper ends of the leaves 4^a as they all swing downwardly and upwardly, one by one or in groups. When the front-most leaf is returned to upright position, the device 5 falls under the influence of gravity to normal position and automatically engages that leaf.

6 indicates the index or index devices comprising an endless web 6^a having a horizontal run below the transparent table 1^a and a vertical run substantially parallel with and close to the path of movement of the front edges of the leaf or holder carrying frames 3.

6^b, 6^b, indicate rollers or shafts around which the web 6^a turns, and 6^c, 6^c, indicate guide rollers to change the direction of run from a horizontal to vertical direction. The web 6^a may itself be of a character of material to permit the entry of names thereon. In that event it may be provided with rulings to form spaces which receive and systematically index the names for the accounts or files carried by the holders 4, but preferably index sheets 6^d, one for each set of holders 4, are detachably secured to one face of the web in a well known manner. As shown in Fig. 5, the index sheets are ruled to form columns and spaces to permit the entry and arrangement of the names and designating marks in systematic order for accurate and ready reference. These sheets 6^d are preferably arranged upon the web 6^a in such position that when one of the frames 3 is in the position indicated in Figs. 1 and 4 whereby the leaves 4^a of a group of leaves may be operated, the index sheet 6^d carrying the names for the accounts or files mounted in that set of leaves, is below the transparent top 1^a.

In order that the endless web 6^a may be automatically moved to bring each of the index sheets 6^d into reference position successively, I provide devices, preferably com-

prising spaced lugs 7, which are carried by the web 6^a and project therefrom into the path of movement of the front edges of the frames 3, as the latter move downwardly. It will be understood by reference to Fig. 1 70 that the lugs 7 are spaced at such distances apart on the web 6^a, and the frames 3 are supported at such points on the chains 2^a, that the movement of the endless device to bring a new frame 3 into operable position 75 will operate to move the endless web a predetermined distance and bring a new index sheet 6^d into reference position below the transparent table 1^a.

The accounts or files in each set of holders may be arranged in any suitable manner, either by number or letter, but preferably they are arranged alphabetically, each set of holders being adapted to carry those accounts or files coming within certain letters of the alphabet, that is, one set of holders may carry all of the files the names of which commence with the letters A and B, and so on.

It will be seen that in a filing appliance 80 constructed according to the present invention, the filing facilities are doubled or tripled in number without materially enlarging the space, and that each set of holders or leaves may be easily and readily brought into operative position adjacent to the table, so that the leaves can be swung downwardly upon the same and the contents of the holder reached, without change of position by the person operating the appliance.

In fact, many alterations in construction and widely differing embodiments and applications of my invention will suggest themselves to those who become skilled or 105 are now skilled in the art of making filing appliances of the class described, without departing from the spirit and scope thereof. My disclosures and description herein, are purely illustrative and are not intended to be in any sense limiting.

What I claim is—

1. In a filing appliance, the combination of a table, an endless movable device, and a plurality of sets of normally upright leaves 115 pivotally supported on said device at spaced intervals from each other, and arranged to be moved thereby to an operative position for swinging the leaves of each set on their pivotal supports forward and downward upon the table.

2. In a filing appliance, the combination of a table, an endless movable device, and a plurality of sets of normally upright leaves pivoted together and fulcrumed by the foremost leaf on said device at spaced intervals from each other, and arranged to be moved thereby to an operative position for swinging the leaves on said fulcrum forward and downward upon the table.

3. In a filing appliance, the combination of a table, an endless movable device, a plurality of sets of normally upright leaves pivotally supported on said device at spaced intervals from each other, and arranged to be moved thereby to an operative position for swinging the leaves of each set on their pivotal supports forward and downward upon the table, and releasable means for locking the leaves in upright position.

4. In a filing appliance, the combination of an endless movable device, a plurality of sets of holders supported on said device at spaced distances from each other and arranged to be moved thereby to an operative position, a freely movable endless web adapted to serve as an index for the said holders, and means between the sets of holders and the web and arranged to be engaged by said sets of holders for moving the said web therewith.

5. In a filing appliance, the combination of an endless movable device, a plurality of sets of holders supported on said device at spaced distances from each other and arranged to be moved thereby to an operative position, a freely movable web adapted to serve as an index for the sets of holders, members carried by the web and arranged to be engaged by the sets of holders for moving the web therewith, and a guide member for guiding each set of holders during its engagement with said members.

6. In a filing appliance, the combination of an endless movable device, a plurality of sets of holders supported on said device at spaced distances from each other and arranged to be moved thereby to an operative position, a plurality of movable indexes, one for each set of holders, movable to and out of an exposed position opposite the operative position for said sets of holders, and means carried by said indexes and arranged to be engaged by said sets of holders successively for moving the indexes successively into and out of exposed position.

7. In a filing appliance, the combination of an endless device, a plurality of sets of slip-holding leaves, means for supporting each of said sets of leaves in spaced position on said endless device, an endless web, arranged to carry indexes, for the said sets of slip-holding leaves, and means controlled by said sets of leaves for moving the said web simultaneously with the endless device predetermined distances.

8. In a filing appliance, the combination of an endless device, a plurality of sets of slip-holding leaves, means for supporting the said sets of slip-holding leaves in spaced position upon said endless device, a web, arranged to carry indexes for the said sets of

bill-holding leaves, and means carried by the said web and coöperating with the supporting means for the sets of slip-holding leaves for operating the said web simultaneously with the said endless device.

9. In a filing appliance, the combination of an endless device, a plurality of frames pivotally mounted in spaced position upon said endless device, a set of pivotally mounted slip-holding leaves carried by each of said frames, a web, arranged to carry indexes, for the sets of slip-holding leaves, and means carried by the said web and projecting into the path of movement of the said frames and arranged to be engaged thereby for moving the said endless web simultaneously with the endless device.

10. In a filing appliance, the combination with a casing having a transparent desk portion, an endless device comprising two chains having up and down runs, a plurality of sets of slip-holding leaves, means for pivotally supporting the said sets of slip-holding leaves between the chains whereby they are arranged in vertical position during the continuous movement of the said endless device, a web arranged to carry indexes, for the said sets of slip-holding leaves, the said web having a horizontal run below the transparent desk portion of the casing, and a vertical run arranged parallel to the path of movement of the supporting means for the sets of slip-holding leaves, and means carried by the said web and projecting into the path of movement of the said supporting means and arranged to be engaged thereby to operate the said web.

11. In a filing appliance, the combination with a casing having a transparent desk portion, an endless device comprising two chains having up and down runs, a plurality of sets of slip-holding leaves, means for pivotally supporting the said sets of slip-holding leaves between the chains whereby they are arranged in vertical position during the continuous movement of the said endless device, a web, arranged to carry indexes, for the said sets of slip-holding leaves, the said web having a horizontal run below the transparent desk portion of the casing, and a vertical run arranged parallel to the path of movement of the supporting means for the sets of slip-holding leaves, and coöperating means between the web and said supporting means for moving the web predetermined distances.

In testimony whereof I affix my signature, in the presence of two witnesses.

HARRY J. HICK.
